UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed April 28, 1928. Serial No. 273,452.

This invention relates to fan-fold typewriting machines, in which, besides the fan-fold work-web, there remains in the machine a condensed record sheet or web upon which 5 are manifolded close together the entries from a long succession of fan-fold forms. The fan-fold web is considerably narrower than the condensed record-web. This wide record-web therefore is held by means of its 10 side margins during manipulation of the overlying relatively narrow web.

This wide record-web is usually held in front of the platen by means of rolls or clamps. It has been found that when the 15 platen was lifted for web-straightening and carbon-stripping purposes respecting the fan-fold web, it often happened that the rear of the condensed record-web would dangle away from the platen and be apt to foul the fan-fold web, which was a detriment. It was 20 also found that, upon restoring the platen to typing position, the dangling record-web would sometimes kink or crease or pucker or make other troubles.

25 These difficulties, it is the aim of this invention to overcome. To this end, there is provided at the delivery side of the platen a temporary clamp or detent for the condensed record-web, that is, for the leading 30 portion thereof; this clamp being releasable to permit the work to advance during the typing operation, but being moved to a closed position preparatory to elevating the platen for giving attention to the fan-fold web. 35 This clamp is placed at some distance above the platen and towards the rear thereof.

Co-operating with the aforesaid clamps there is also provided a separate table or plate at the intake side of the platen between the platen and the introductory shelf 40 over which the fan-fold runs. Provision is made for clamping the following end of the record-web to this auxiliary table. The web is therefore clamped both at its front end 45 and at its rear end, and in this condition is held upon the platen so that, during the raising and lowering of the platen, said record-web cannot become displaced or foul the fan-fold web or any part of the machine.

50 An advantageous use can be made of the

present invention in manifolding a succession of sets of extra short carbon-interleaved forms constituting a fan-fold web, and making a condensed record thereof. Such forms usually contain only one line of data, and 55 are often too short to be efficiently handled in a usual continuous billing typewriting machine, since using it would require too many carbon-stripping operations. It is a feature of the present invention to provide means 60 for efficiently typing short forms and making a condensed record of the data typed thereon with a minimum of carbon-stripping operations. To this end, devices are provided for raising the platen slightly which co-operate 65 with the work-sheet-clamping means of the present invention which grip a condensed record-web securely taut at both sides of the platen against being kinked or dragged forward while the overlying form-bearing work-web is pulled ahead, to bring a new form to 70 printing position. Thereafter the carbons are stripped from several typed forms at one operation.

Other features and advantages will hereinafter appear.

In the accompanying drawings, Figure 1 is a fragmentary, perspective view of a carriage of an Underwood continuous billing typewriting machine having my invention applied thereto.

Figure 2 is a fragmentary, cross-sectional view, from front to rear, of the structure shown in Figure 1. The record-web clamps of the present invention are shown locked in 80 released position.

Figure 3 is a view similar to Figure 2, the record-web clamps being shown in effective position.

Figure 4 is a diagrammatic view illustrating the operation of unlocking the platen-displacing frame and raising it slightly off the feed-rolls preparatory to pulling the work-web ahead, the record-web being clamped against falling away from the platen. 90

Figure 5 is a diagrammatic view similar to Figure 4, in which the platen is shown lowered again to engage against the lower feed-rolls.

Figure 6 is a diagrammatic view illustrat-

100

ing how the interleaved carbons are stripped from several successive, typed forms at one operation, the record-web being clamped against falling onto the lower form-bearing work-web.

5 The present invention is illustrated in connection with an Underwood continuous billing typewriting machine, in which types 10 strike against the platen 11 upon a platen-shaft 12, journaled in a right-hand end plate 13 and a left-hand end plate 14 on a platen-displacing frame 15, which is pivotally mounted on a carriage 16. For line-spacing the platen 11, instrumentalities are provided, including a line-spacing ratchet-wheel 17, which instrumentalities are effective to rotate a gear 18 which, acting through a pinion 19 on a stub-axle 20 on the carriage, rotates a gear 21 on the platen-shaft 12. 20 Lower-feed-rolls 22 engage against the platen 11, and instrumentalities for guiding a multiple-ply work-web 23 between the feed-rolls and the platen may include a rear paper-table 24.

25 Carbons 25 may be held interleaved between the plies of the web 23 by a carbon-carrier 26, which runs on a track 27 in the rear of the carriage. The forward end of the track is supported on a pair of brackets 28, fastened to the carriage. Two side-edge guides 29 for the web 23 may be mounted on a cross-rod 30, extending between the brackets 28, and guide the web laterally to the platen.

35 The parts described hereinbefore may be of the same construction as usual in an Underwood standard continuous billing typewriting machine.

A typewriting machine embodying the 40 present invention may be advantageously used for manifolding a line of data on each of a series of sets of short forms 31 previously printed on the web 23, and making a condensed record of such data on a wider 45 underlying record web or sheet 32, laterally positioned on the platen by means hereinafter described, so that both of its side-edge portions extend out beyond the side edges of the web 23. For doing this kind of condensed- 50 record work expeditiously with a minimum of operations, it is a feature of the present invention to provide means whereby it is convenient to type several sets of the forms 31 before stripping the carbons therefrom and 55 severing the typed forms, instead of stripping the carbons from each set immediately after it is typed, which has usually been done heretofore.

To this end, means are provided for holding 60 the record-web stationary on the platen while a typed set of forms is pulled ahead relatively to the record-web for bringing another set of forms to typing position. One embodiment of the record-web-holding means 65 includes an auxiliary rear paper-table 35 for

the record-web, above the usual paper-table 24, over which the work-web 23 is conducted. The table 35 is supported by two forwardly and downwardly extending arms 36, each being integrally joined to an inreaching angle-piece 37. The angle-piece forms an integral part of an upwardly and rearwardly extending bracket-member 38, fastened on each end plate of the platen-displacing frame. A portion 39 of each angle-piece 37 is disposed in a plane which intersects the axis of the platen at a right angle, and is positioned for serving as a side-edge guide for the record-web.

To co-operate with the table 35 and to grip thereagainst the record-web 32, two clamping arms 40 are provided, each having a rubber shoe 41 at its lower end, and each being adjustably fastened to a rock-shaft 42 journaled in the brackets 38. The arms 40 extend downwardly and slightly forwardly from the shaft 42, and are urged toward the table 35 by fastening a forwardly-extending arm 43 and a like arm 44 on the right and the left end of the shaft 42, respectively. Two tensile springs 45 each have one end fastened to a screw 46 in the adjacent end plate on the platen-displacing frame, the upper end of one spring being fastened to the outer end of the arm 43, and the upper end of the other spring being fastened to a right-hand portion of a laterally-disposed pin 47, fast in the forward end of the arm 44 on the right side thereof. The pin 47 passes through the arm and has a portion disposed on the left side of the arm 44 for a purpose to presently appear.

It is a feature of the present invention to provide devices which will clamp the record-web at the delivery side of the platen in co-operation with the clamping arms 40, thereby holding the record-web 32 securely taut on the platen, regardless of its movement upwardly when displaced, or the movement of the work-web 23 over the record-web. To this end, a paper-table 50 is fastened between the end plates 13 and 14 at the delivery side of the platen for conducting thereover both the web 23 and the record-web 32 as the typing proceeds. For gripping the side edges of the record-web 32 against the table, clear of the side edges of the web 23, two downwardly and forwardly extending clamping arms 51 are loosely mounted on the shaft 42, and have inreaching extensions or tabs 52 provided with rubber friction shoes 53, which are arranged for engaging squarely against the table 50. For urging the tabs downwardly toward the table, two helical springs 54 are coiled around the shaft 42, one spring being positioned adjacent each arm 51, inwardly therefrom. The inner end of each spring 54 is fastened to a collar 55, which may be riveted to the shaft 42. The other end of each spring 54 terminates in a forwardly-extending portion disposed alongside the adja-

70

100

105

110

115

120

125

130

cent arm 51, and having an inreaching hook 57 which engages over the top edge of the arm.

By arranging each spring with a small amount of initial tension, it is effective for urging the adjacent arm downward, and permits the tabs 52 to engage against the table 50 independently of the engagement of the arms 40 against the table 35.

10 It is another feature of the present invention to have the clamping means at both the introductory side and the delivery side of the platen controlled by a single operating instrumentality. To this end, a forwardly-extending lifting arm 58 is fastened on the shaft 42 outward from each clamping arm 51 and adjacent thereto. An inreaching lug 59, on the end of each arm 58, is disposed for engaging against the lower edge of the adjacent 15 arm 51 and raising its tab 52 from the table 50 upon clockwise rotation of the shaft 42, which rotation it will be noted is also effective to swing the clamping arms 40 up from the table 35.

20 During normal typing operations, the clamping arms 40 and 51 are locked in released or ineffective condition above the tables 35 and 50, respectively, by instrumentalities including a locking lever generally 25 designated as 60, which is pivoted against the right face of the left-hand bracket-member 38 on a screw 61 positioned forwardly from the shaft 42. The lever 60 has an upwardly-extending operating arm 62 terminating in 30 a leftwardly-bent finger-piece 63, and has a short rearwardly-extending arm 64 whose rear end is provided with a concave locking notch 65.

In effective condition of the clamping arms 40 and 51, a roller 66, revolubly mounted on the left-hand end of the pin 47, is disposed in the corner of the arms 62 and 64 (Figure 1), and bears down against the upper edge of the arm 64. A depending toe 67, on the lower-45 edge portion of the arm 64 adjacent the rear end thereof, engages against the upper edge of the left-hand end plate 14 and limits the downward movement of the arm 64, due to the pull of the left-hand spring 45 on the pin 50 47. A heel 68 on the lever 60 is arranged for engaging against the end plate 14 and arresting the counterclockwise movement of the arm 64 when it is in locking position.

To release the record-web-clamping arms 55 40 and 51 and lock them in released position, the finger-piece 63 is pulled forward. This swings the arm 64 counterclockwise, and the roller 66 will be cammed upward and will ride rearwardly over the upper edge of the 60 arm until it reaches the outer end and is seated in the locking notch 65. It will be noted that the shaft 42 and screw 61 are fixed relatively to each other, which construction prevents the force of the spring 45 from pushing the 65 shaft and screw apart by means of the toggle-

joint action of the arms 44 and 64. The co-action of the arm 44, the spring 45, the roller 66, and the notched arm 64, is effective for securely locking the clamping arms 40 and 51 in released positions (Figure 3), while permitting them to be made effective by a light rearward push of an operative's finger on the finger-piece 63, which will cause the roller 66 to ride out of the notch 65, which permits the arm 44 to then be pulled downward as the arm 62 swings to the rear.

It will also be noted that due to the much greater length of the arm 62 relative to the arm 64, and further because of the camming action of the latter arm upon the roller 66, a light pull forwardly on the finger-piece 63 is sufficient to raise the clamping arms 40 and 51 and lock them in ineffective positions.

According to one use of a continuous billing typewriting machine embodying the present invention, a plurality of the sets of short forms 31 are typed one after another before any set is severed from the web 23. To make a condensed record on the sheet 32 of the data typed on the forms 31, the operation is as follows. After typing a line of data, the clamping arms 40 and 51 being normally released, both the web 23 and the record-web 32 are line-spaced ahead by the line-spacing ratchet-wheel 17, enough to give the desired condensed record spacing on the web 32. The clamping arms 40 and 51 may then be made effective to grip the record-web by the operative conveniently pushing the finger-piece 63 rearwardly with the middle finger of her left hand until the lever 60 is stopped by the toe 67 coming against the end plate 14. At that point in the movement of the finger-piece 63, the operative's first or index finger is closely adjacent a finger-piece 70 of a locking lever generally designated as 71, which may be pivoted about a shaft 72 in the carriage 16, and is effective to lock the platen-displacing frame 15 down by means of a notch 73, which engages about a pin 74 in the end plate 14 of the platen-displacing frame. The lower edge of the notch 73 may be constructed to serve as a cam, so that rearward movement of the finger-piece 70, by said index finger of the operative will press the pin 74 upward and raise the platen 11 off the feed-rolls 22 (Figure 5). The construction and principle of operation of the lever 71, except as hereinafter noted, may be the same as is disclosed in my co-pending application No. 202,631, filed June 30, 1927.

The lever 71 is provided with means for arresting its rearward swing, which means includes a novel integral hook 75 formed on the lower edge of the notch 73 for engagement against the pin 74. It will be noted that the finger-piece 70 extends rightwardly whereby the finger-piece 63 may be moved substantially alongside it.

The lever 71 is normally urged forward by

a spring-device (not shown), and a portion 71^a positioned above the notch 73 has a cam-edge 71^b for engagement with the pin 74 when it is lowered subsequently to the raising of the platen to carbon-stripping position. The pin striking the edge 71^b cams the lever 71 rearwardly so as to permit the pin to engage in the locking notch 73. The lever-portion terminates a short distance to the rear of the hock 75 whereby the platen may be raised slightly off the feed-rolls by the lever 71; the last typed form gaged to tearing-off position; and the platen then further raised to carbon-stripping position.

15 The platen being raised, the web 23 is freed from engagement with the feed-rolls 22, and the typed form may be pulled ahead over the clamped record-web without kinking it or moving it ahead. The next succeeding form is gaged to typing position by the operative's right hand pulling the leading edge of the typed form to the upper edge of a gage-bar 76, which is fastened between brackets 77 mounted on the angle-pieces 37. Each bracket has an upright portion 78 which may substantially align with the angle-piece gageportion 39, and serve as a side-edge guide for the typed portion of the record-web as it is fed rearwardly.

20 Side-edge guides 80 for the web 23 are mounted on the gage-bar 76 for lateral adjustment by means of elongated slots 81 in base-portions 82 of the guides, and screws 83, which, passing downwardly through the 25 slots, are threaded in the gage-bar.

25 After gaging the leading untyped form 31 to typing position, the lever 71 will be released and the platen-displacing frame will descend against the feed-rolls 22, as indicated in Figure 5. This gaged form and succeeding ones will be typed and moved ahead, as described above. After typing the last form of a group or set, the platen will be line-spaced, the clamping arms made effective, and the platen will be swung up to usual carbon-stripping position, and all the typed forms straightened out, as illustrated in Figure 6, and the last typed form will be gaged to tearing-off position. The carbons 25 will now be stripped rearwardly in the usual way, and the platen lowered to typing position (Figure 3), the clamping arms still remaining in effective positions. The typed group of forms may now be severed from the web 50 28. This will usually be done by the operative pressing the last typed form against the paper-table 50 and tearing it from the web along a usual perforated line 85, between the last typed form and the next succeeding untyped form. In cases where very short forms 31 are employed, it may be desirable that the last typed form is not severed with the preceding typed forms, but left connected to the succeeding untyped forms for gaging purposes.

A usual knife 86 serves as a guiding means for the work-web 23, but will ordinarily not be used for severing the web 23, according to the above-described use of my invention, with short forms. It can be readily seen, however, by those skilled in the art that a continuous billing typewriting machine embodying the present invention can be used in many cases for ordinary continuous billing work, and in such cases the knife will be used in the usual way.

70 After severing a group of typed forms, the platen will be lowered to normal typing position, and the clamping arms will be released, and the next cycle of operations performed as described above.

75 Variations may be resorted to within the scope of the invention, and portions of the improvements may be used without others.

Having thus described my invention, I claim:

1. In a web-manifolding carbon-stripping typewriting machine, the combination of a platen-displacing frame, a revoluble platen in said frame around which may be fed from the rear a multiple-ply, form-bearing, carbon-interleaved work-web and a wider underlying record-web having both side edges exposed, lower feed-rolls, a clamping device on said frame for clamping said record-web at the introductory side of said platen free of said work-web, a clamping device on said frame at the delivery side of said platen arranged for clamping the side edges of said record-web clear of said work-web, and releasable instrumentalities effective for locking said clamping devices in ineffective positions to permit said record-web to be line-spaced ahead with said work-web as the typing proceeds, said clamping devices effective to grip said record-web and hold it taut around said platen upon elevating the latter for stripping said carbons, whereby said record-web will be held against falling down onto said work-web and being kinked or otherwise fouled.

100 2. In a web-manifolding carbon-stripping typewriting machine, the combination of a revoluble platen around which may be fed from the rear a multiple-ply, carbon-interleaved, form-bearing work-web and a wider underlying record-sheet having both side edges exposed, means for displacing said platen upwardly for stripping the carbons from one form of said web to a succeeding form, a clamping device at the delivery side of said platen for gripping said record-sheet, and a clamping device at the introductory side of said platen for gripping said record-sheet, said clamping devices being movable with said platen and effective to grip said record-sheet and hold it taut around said platen when the latter is in its displaced position, whereby said record-sheet is prevented from dropping on said work-web and 105 110 115 120 125 130

being thereby wrinkled or otherwise fouled.

3. In a web-manifolding carbon-stripping typewriting machine having an upwardly displaceable platen-frame, the combination of a revoluble platen in said frame around which may be fed from the rear a multiple-ply, carbon-interleaved work-web and a wider underlying record-sheet having both side edges exposed, a clamp-device mounted on said frame at the delivery side of said platen effective for gripping said record-sheet at each side of said web, and a clamp-device mounted on said frame at the introductory side of said platen effective for gripping said record-sheet free of said work-web, said clamp-devices co-operating to hold said record-sheet taut around said platen in its upwardly displaced position and fast against movement by the friction of said work-web when moved ahead relative to said record-sheet.

4. In a typewriting machine of the class described, the combination of a platen around which may be fed from the rear a multiple-ply work-web interleaved with carbons and a wider underlying record-sheet having both side edges exposed, means for displacing said platen upwardly for straightening said web under said platen and stripping said carbons, and means for clamping said record-sheet on each side of said platen free of said work-web to hold said sheet against falling by gravity away from said platen onto said work-web when the platen is displaced upwardly away from said work-web.

5. In a web-manifolding carbon-stripping typewriting machine, the combination of a platen-displacing frame, a platen in said frame around which may be fed from the rear a 40 multiple-ply, carbon-interleaved work-web and a wider underlying record-sheet having both side edges exposed, a paper-table mounted on said frame at the delivery side of said platen, over which both of the work-pieces 45 pass to the rear, a paper-table on said frame at the introductory side of said platen over which said record-sheet is conducted to said platen, said work-web passing below said last-mentioned table, a clamping device co-operating 50 with said first-mentioned table for gripping the side edges of said record-sheet clear of said work-web, a clamping device on said frame effective for gripping said record-sheet against said second-named table, said clamping 55 devices being normally released, and means supported on said frame for rendering each of said clamping devices effective at one operation preliminary to the upward displacement of said platen, whereby said record-sheet is held against falling on said record-web and movement of the latter ahead is 60 without effect on the position of said record-sheet relative to the printing line.

6. The structure described in claim 5, characterized by said means which controls both

of said clamping devices, including a lateral rock-shaft on said frame having said clamping devices operatively fastened thereto, and a lever-system effective for rotating said shaft against spring tension to clamp-releasing position.

7. In a web-manifolding carbon-stripping typewriting machine, the combination of a platen-displacing frame, a platen in said frame around which may be fed from the rear a multiple-ply, carbon-interleaved work-web and a wider underlying record-sheet having both side edges exposed, a paper-table mounted on said frame at the delivery side of said platen, over which both of the work-pieces pass to the rear, a paper-table on said frame at the introductory side of said platen over which said record-sheet is conducted to said platen, said work-web passing below said last-mentioned table, a clamping device co-operating with said first-mentioned table for gripping the side edges of said record-sheet clear of said work-web, a clamping device

on said frame effective for gripping said record-sheet against said second-named table, said clamping devices being normally released, means supported on said frame for rendering each of said clamping devices effective at one operation preliminary to the upward displacement of said platen, whereby said record-sheet is held against falling on said record-web and movement of the latter ahead is without effect on the position of said record-sheet relative to the printing line, said means which controls both of said clamping devices including a lateral rock-shaft on said frame having said clamping devices operatively fastened thereto, and a lever-system effective for rotating said shaft against spring tension to clamp-releasing position, said lever-system including instrumentalities for latching said shaft in a position which will hold said clamping devices in ineffective positions.

8. In a web-manifolding carbon-stripping typewriting machine, the combination of a platen-carriage, a platen-displacing frame pivotally mounted on said carriage, a platen in said frame around which may be fed from the rear a multiple-ply work-web bearing a succession of sets of short forms interleaved with carbons and a wider underlying record-sheet having both side edges exposed, lower feed-rolls engaging against said platen, a clamping device at the introductory side of said platen effective for clamping said record-sheet without affecting said work-web, a clamping device at the delivery side of said platen for gripping the exposed side edges of said record-sheet free of said work-web, both of said clamping devices being normally ineffective, typing instrumentalities for typing a line of data on a form of said work-web which is carbon-copied on said record-sheet, line-spacing means for line-spacing 110 115 120 125 130

together both said work-web and said record-sheet ahead, instrumentalities on said platen-displacing frame for making both of said clamping devices effective, and a lever on said carriage effective for raising said platen slightly above said feed-rolls to permit said work-web to be pulled ahead to bring the next succeeding untyped form to typing position, said clamps being effective to hold said record-sheet taut on said raised platen against the friction of said work-web when the latter is pulled ahead.

9. In a continuous billing typewriting machine, the combination of a platen-displacing frame, a platen around which may be fed a multiple-ply work-web bearing sets of short forms interleaved with carbons and a wider underlying record-sheet having both side edges exposed, means for clamping said record-sheet at both the introductory and the delivery side of said platen against movement therearound, and releasable means for locking said clamping means in ineffective position, said clamping means including a lateral rock-shaft supported by said displacing frame in the rear of said platen, a paper-table supported by said displacing frame below said shaft at the introductory side of said platen for having fed thereover said record-sheet separate from and above said work-web, two depending clamping members mounted on said shaft and having their lower ends arranged for pressing said record-sheet against said table upon counterclockwise rotation of said shaft, a paper-table supported on said displacing frame at the delivery side of said platen over which said work-web and said record-sheet are conducted rearwardly, two spring-urged clamping members supported on said rock-shaft for gripping the side edges of said record-sheet against said last-mentioned paper-table, and instrumentalities for releasing said last-named members upon clockwise rotation of said shaft.

45 10. The structure described in claim 9, characterized by said instrumentalities including lifting arms on the rock-shaft engaging under said last-named members upon clockwise rotation of said shaft.

50 11. The structure described in claim 9, characterized by said instrumentalities including lifting arms on the rock-shaft engaging under said last-named members upon clockwise rotation of said shaft, and means which effects the firm engagement of each set of the clamping members mounted on the rock-shaft against its associated paper-table irrespective of the engagement of the other set against its associated table.

60 12. The structure described in claim 9, characterized by said instrumentalities including lifting arms on the rock-shaft engaging under said last-named members upon clockwise rotation of said shaft, and means which effects the firm engagement of each

set of the clamping members mounted on the rock-shaft against its associated paper-table irrespective of the engagement of the other set against its associated table, said means which effects the firm engagement of said clamping members including a loose mounting on said shaft for the clamping members at the delivery side of said platen, and springs urging said members toward their associated paper-table.

70 13. In a typewriting machine of the class described, in combination, a platen around which may be fed a work-web interleaved with carbons and a wider underlying record-sheet having both side edges exposed, and means for clamping said record-sheet at the introductory side of said platen free of said work-web, including a lateral shaft disposed at the rear of said platen, a paper-table, and two clamping members on said shaft arranged for engaging against said table, said table being positioned so that said work-web may be fed below it to said platen.

75 14. In a typewriting machine of the class described, in combination, a platen around which may be fed a work-sheet, lower feed-rolls engaging said work-sheet against said platen, a clamping device at the introductory side of said platen normally ineffective, instrumentalities including a lever which are effective when said lever is disposed in its forward position to lock said clamping devices in ineffective positions, said instrumentalities being arranged for rendering said clamping devices effective upon movement of said lever rearwardly, and a second lever effective for raising said platen by movement rearwardly, said first-named lever when moved to its rearmost position being disposed in convenient proximity to said second-named lever, whereby an operative may first operate said first-named lever and thereafter said second-named lever with one hand in substantially one continuous operative movement.

80 15. In a typewriting machine of the class described, the combination with a revoluble platen around which a work-sheet may be fed, of a clamping device for gripping said work-sheet at the introductory side of said platen, a clamping device for gripping said work-sheet at the delivery side of said platen, and instrumentalities including a lever-system effective for moving each of said clamping devices to ineffective positions, said lever-system carrying means effective to lock said clamping devices automatically in ineffective position.

85 16. The structure described in claim 15, characterized by the locking means including a lever-arm having a notch in its end, a second spring-urged lever-arm oppositely disposed to said first-named arm in an adjacent parallel plane, and devices carried by said second-named lever-arm arranged to be seat-

130

ed in said notch upon operative movement of said first-named arm to locking position, whereby the latter lever-arm is locked against spring-urged movement.

17. The structure described in claim 15, characterized by the locking means including a lever-arm having a notch in its end, a second spring-urged lever-arm oppositely disposed to said first-named arm in an adjacent parallel plane, and devices carried by said second-named lever-arm arranged to be seated in said notch upon operative movement of said first-named arm to locking position, whereby the latter lever-arm is locked against spring-urged movement, said devices on the second-named arm including a lateral pin and roller, and further characterized by the notch in the first-named arm being formed to permit said roller to ride out of said notch upon releasing movement of said first-named arm.

18. In a typewriting machine of the class described, in combination, a carriage, a platen around which may be fed from the rear a work-sheet, means for displacing said platen upwardly, including an upwardly-extending lever on said carriage mounted adjacent the left hand of said platen and having a rightwardly-extending finger-piece, spring-pressed clamping devices effective for clamping said work-sheet at the introductory and delivery sides of said platen, said clamping devices being normally locked in ineffective position, and instrumentalities for unlocking said clamping devices whereby they may be returned by spring-pressure to effective position, said instrumentalities including an upwardly-extending lever positioned forwardly from and in a leftwardly-adjacent plane relative to said first-named lever, said last-named lever having a leftwardly-extending finger-piece so positioned that upon movement by an operative of said last-named lever rearwardly adjacent said first-named lever with the middle finger of her left hand, the first finger of her left hand is brought approximately into engagement with the finger-piece of said first-named lever.

19. The structure described in claim 17, characterized by means for stopping the notched lever when it has been moved to a position wherein the devices are seated in the notch.
